UNITED STATES PATENT OFFICE.

CHRISTIAN E. SCHAFER, OF EAST CLEVELAND, OHIO.

DESIGN FOR A TRAY OR RECEPTACLE.

51,466.

Specification for Design.

Patented Nov. 6, 1917.

Application filed September 22, 1917. Serial No. 192,819. Term of patent 7 years.

To all whom it may concern:

Be it known that I, CHRISTIAN E. SCHAFER, a citizen of the United States, residing at East Cleveland, in the county of Cuyahoga and State of Ohio, have invented a new, original, and ornamental Design for Trays or Receptacles, of which the following is a specification, reference being had to the accompanying drawing, forming part thereof.

In said drawing, Figure 1 is a perspective view, and Fig. 2 a top plan, of a tray or receptacle, showing my new design.

I claim:

The ornamental design for a tray or receptacle, as shown.

CHRISTIAN E. SCHAFER.
